Assistant Examiner — Antoinette Martine Suiter

(57) **CLAIM**

The ornamental design for a cable tester, as shown and described.

DESCRIPTION

FIG. 1 is a front view of a cable tester according to this disclosure;

FIG. 2 is a back view of the cable tester of FIG. 1;

FIG. 3 is a left side view of the cable tester of FIGS. 1 and 2;

FIG. 4 is a right side view of the cable tester of FIGS. 1-3;

FIG. 5 is a bottom view of the cable tester of FIGS. 1-4;

FIG. 6 is a top view of the cable tester of FIGS. 1-5;

FIG. 7 is a perspective view from the front, above, and right of the cable tester of FIGS. 1-6;

FIG. 8 is a perspective view from the back, above, and left of the cable tester of FIGS. 1-7; and,

FIG. 9 is a perspective view from the front, below, and right of the cable tester of FIGS. 1-8.

The broken lines shown are included for the purpose of illustrating portions of the cable tester that form no part of the claim.

1 Claim, 6 Drawing Sheets
